APPARATUS FOR THE PRODUCTION OF
ARTIFICIAL THREAD

Ovid S. Petrescu, Nashville, Tenn., assignor, by
mesne assignments, to E. I. du Pont de Nemours
& Company, Wilmington, Del., a corporation
of Delaware

Application September 26, 1934, Serial No. 745,575

1 Claim. (Cl. 117—27.5.

This invention relates to bucket apparatus to be used in the centrifugal process for the production of artificial thread, and more particularly, it relates to washing, wringing, and spinning buckets from which liquid adhering to the thread may be more efficiently removed by centrifugal force, which has greater strength to withstand high speed operation, and in which the artificial thread is more completely protected against damage from treating liquids.

In the manufacture of artificial thread from viscose, centrifugal buckets may be used for a great many purposes. The thread may first be spun into a centrifugal bucket to produce what is commonly known in the art as a bucket cake. The bucket cake may be treated in a centrifugal bucket with various treating solutions, in which case, the treating solutions, such as washing liquids, bleaching liquids or desulfurizing liquids are passed through the cake by centrifugal force. It may further be desired to remove as much liquid as possible from the cakes which have been treated with the treating solutions, and this is commonly done by submitting the cakes to wringing or whizzing at high speeds in centrifugal buckets. In all of these operations, it is of primary importance to remove liquid adhering to the thread or cake and passing it from the bucket. The constant tendency of the artificial thread manufacturing industry is to increase the speed of centrifugal buckets to gain increased efficiency of production. The speed at which buckets may be rotated is at present materially limited because of the bucket construction which is necessary to obtain the desired draining of the liquids therefrom without undue corrosion of the bucket and damaging of the yarn by contamination with products of corrosion.

To properly drain the liquids from the bucket, it was found necessary to perforate the walls of the same so that the said liquids may be forced therefrom. To prevent contamination of the yarn, the buckets must be made of a material which is inert to the various treating solutions. Since none but very expensive, and consequently uneconomical, commercially available metals are entirely inert to the treating solutions commonly used, the art has almost uniformly adopted resinous condensation products, such as, for example, a phenol formaldehyde condensation product, for the construction of buckets or bucket liners.

Various attempts have been made to improve the construction of centrifugal buckets so as to be able to increase the speed with which the buckets are rotated. These improvements in-

clude the moulding of buckets from plastic material in which is embedded fabric, metallic bands, wire or similar reinforcing materials. Buckets have also been made of aluminum, aluminum alloy or other metals, and other improvements have been made in which metal wire, bands, or a sheet covers the outer periphery of the moulded bucket. In all of these prior art improvements, the buckets were provided with perforations through the walls thereof, and due to the high corrosive action of treatment liquors, they were soon rendered worthless and the products of corrosion often produced irreparable damage to the thread.

It has furthermore been suggested that buckets be made of metal such as aluminum with a liner of suitably inert material such as a resinous condensation product and in which drainage perforations are provided only through the said liner, the liquids being passed laterally through the liner and outwardly through a suitable bore or groove between the liner and the outer shell.

Although the latter improvement has permitted a material increase in the bucket strength with a consequent increase in bucket speed, there are some disadvantageous features in this construction in that it does not sufficiently prevent deleterious corrosion of the outer metallic shell and that it does not entirely eliminate contacting of the yarn with products of corrosion.

It is therefore an object of this invention to provide a new and improved centrifugal bucket for the production of artificial threads.

It is another object of this invention to provide a new and improved centrifugal bucket comprising a metal and an interliner in which corrosion of the metal is very materially reduced.

It is a still further object of this invention to provide a centrifugal bucket for the production of artificial thread in which neither the liner nor the outer shell has perforations therein.

A still further object of this invention is the production of a centrifugal bucket liner which is efficient, of low cost production and easy to fabricate.

Other objects of the invention will appear hereinafter.

The objects of the invention are accomplished in general by constructing a bucket with a strong shell, preferably of metal, and a liner of corrosion-resisting material, said liner being provided with axial grooves on the inner surface thereof, and constructed in such a manner as to discharge the liquids upwardly through the top

of the bucket, without passing through either the liner or the shell.

The details of the invention and the advantages thereof will become more clearly apparent by reference to the following description taken in connection with the accompanying illustrations in which:

Fig. 1 is a vertical sectional view of a wringing bucket shell and liner constructed in accordance 10 with this invention.

Fig. 2 is a top plan view of the wringing bucket shown in Fig. 1.

Fig. 3 is a vertical sectional view of a washing bucket and liner therefor, constructed in accordance 15 with this invention.

Fig. 4 is a top plan view of the liquid treatment bucket shown in Fig. 3.

Fig. 5 is a vertical sectional view of a liner for a spinning bucket constructed in accordance with 20 this invention.

Fig. 6 is a fragmentary view of a washing bucket liner showing a modified form of groove.

Referring more in detail to the drawings, reference character "11" designates a wringing bucket shell which is preferably composed of a corrosion resistant material having a high tensile strength such as, for example, forged aluminum, Monel metal, or stainless steel. The shell 11 is provided with an externally projecting flange 13 through which it may be fastened to the flange of a drive shaft (not shown) by means of screws or bolts. The shell is also provided with an internally projecting member 18 opposite the flange 13. The flange 13 and member 18 are provided 30 with a common bore 12 for reception of the drive shaft by means of which the bucket is to be rotated. Due to the provision of this internally projecting member 18, the flange 13 may be positioned closely adjacent the bottom of the bucket, thus adding materially to the strength of the bucket and eliminating any undesirable wobbling thereof. This is particularly important in the 40 construction of wringing buckets in view of their high rotational speed, as a result of which severely, unbalancing forces are set up. A bucket liner 14 is fitted snugly into the internal surface of the shell 11. This liner is preferably composed of a material substantially chemically inert to the liquid content of the bucket cake, such 45 as hard rubber, or a resinous condensation product. The liner 14 is imperforate and substantially covers all portions of the shell 11 which might otherwise be contacted by the bucket cake.

Inasmuch as bucket cakes, which are to be 55 subjected to a wringing operation, are somewhat uneven and contain a certain amount of slack, the wringing bucket liner 14 is constructed with a plurality of somewhat flattened internal portions 17 which are adapted to take up such slack 60 and unevenness of the cake. Due to the high speeds at which wringing buckets are rotated, the flattened portions 17 eliminate injury to the thread by preventing rotation of the bucket relative to the bucket cake. The internal surface of 65 the bucket is provided with a plurality of comparatively narrow, axially extending grooves 15 for removal of the liquid forced from the bucket cake. The width of these grooves is of the order of $\frac{1}{2}$ to $\frac{1}{4}$ of an inch, and in the wringing bucket illustrated by Figs. 1 and 2 they are preferably 70 about $\frac{1}{8}$ of an inch in width. The depth of the grooves may vary between $\frac{1}{2}$ and $\frac{1}{4}$ of an inch and is preferably about $\frac{1}{8}$ of an inch. The upper portion of the liner 14 is constructed with an internally bevelled edge 16 so that the bucket cake 75

may be easily inserted into the bucket with which it has a comparatively snug fit.

The bucket illustrated in Figs. 3 and 4 is particularly adapted for the liquid treatment of bucket cakes, such as, washing, desulfuring, 5 bleaching, etc. Since these operations are usually carried out at considerably lower speeds than the above described wringing operation, and inasmuch as a great volume of treating liquid is ordinarily forced through the bucket cakes in 10 the liquid treatment thereof, the flattened portions, the internally bevelled edge and the internal projection in the bottom of the bucket may be dispensed with in the washing bucket. The washing bucket comprises an external, preferably 15 corrosion resistant, metal shell 21, having a flanged extension 23 and a drive shaft bore 22. The liner 24 of the bucket is preferably provided with a downwardly offset bottom 26 and an inclined shoulder 27, whereby the lower portions 20 of the cake will be contacted with treating liquid to approximately the same extent as the other portions thereof. The liner 24 is provided on its internal surface with axially extending 25 grooves similar to the grooves in the wringing bucket. These grooves may vary considerably in width, but are preferably kept at approximately the same width as those of the wringing bucket to prevent damaging the bucket cake thread. Since these grooves must be made rather narrow 30 to prevent damaging the thread, but must necessarily conduct a large volume of liquid from the bucket, they may be constructed in the manner shown by Fig. 6, in which 24 designates a section 35 of the liner. The liner is provided with enlarged grooves 28 which communicate with the internal surface through the comparatively narrow slots 25, thus allowing the removal of a large volume of liquid without the use of large gaps between adjacent portions of the bucket. Alternatively, 40 the grooves in the washing bucket may be made of greater depth to take care of the large volume of liquid.

Fig. 5 shows a liner for a spinning bucket. This liner is preferably made with an outside 45 section 31 of a resinous condensation product, such as a phenol-formaldehyde condensation product, reinforced with a fabric, and an inside section 33 of a smooth surfaced resinous condensation product. The inner surface of the 50 spinning bucket liner is provided with axially extending grooves 34 similar to the grooves of the wringing and washing buckets. The grooves 34 are preferably made considerably narrower than the grooves 15 and 25 to prevent deformation of 55 the freshly formed and somewhat plastic fiber when it is forced against the side walls of the spinning bucket. The number of grooves can also be materially reduced inasmuch as the volume of coagulating fluid adhering to the thread and 60 which is to be removed from the bucket is comparatively small. The depth of the grooves 34 is preferably about $\frac{1}{8}$ of an inch through the greatest part of their length, but adjacent the top 65 of the bucket upon which a cover (not shown) is usually positioned, the slots are shown by numeral 35 as being upwardly inclined and of considerably greater depth so as to permit the fluid to pass around the cover and to remove, more efficiently, the liquid therefrom. Obviously, this liner can 70 be made of a single piece instead of the two-piece construction shown.

In the various modifications illustrated, the liquid is drained from the cake by centrifugal force and is collected in the axially extending 75

grooves. The liquid travels upwardly in the grooves in a substantially vertical direction to be thrown from the bucket adjacent the upper edge thereof.

5 The liquid, as passed from the bucket, cannot contact the metallic outer shell and again flow back into contact with the yarn of the cake. Such liquids as remain in the bucket to recontact the yarn will not have had any contact 10 with the metallic portions of the bucket, thus eliminating the damaging of thread by contact with products of corrosion.

15 A further advantage, derived from the use of the imperforate shell and liner, is that buckets of greatly increased strength can be manufactured, and with very little danger that the buckets will deteriorate from corrosive action of treating liquids accumulating between the shell and liner. Consequently, considerably greater rotational 20 speeds can be safely employed than were possible heretofore. Furthermore, the cost of the buckets

can be very materially reduced in view of the simple design.

Since it is obvious that various changes and modifications may be made in the above description and accompanying illustrations, without departing from the nature and spirit thereof, it is to be understood that the invention is not to be limited thereto except as set forth in the appended claim.

I claim:

10 In a centrifugal bucket for the production and treatment of a bucket cake, an imperforate side wall, the thread-contacting surface of which is composed of a substance which is substantially inert to liquids used in the production and treatment of said artificial thread, a plurality of axially extending grooves in the said side wall surface thereof, and narrow slits connecting the said grooves with the thread-contacting surface of said side wall. 15
